UNITED STATES PATENT OFFICE

148,946

DESIGN FOR A PLAYING CARD

George J. O'Donnell, Waterbury, Conn.

Application August 27, 1946, Serial No. 132,905

Term of patent 14 years

(Cl. D34—13)

To all whom it may concern:

Be it known that I, George J. O'Donnell, a citizen of the United States of America, residing in Waterbury, county of New Haven, and State of Connecticut, have invented a new, original, and ornamental Design for a Playing Card, of which the following is a specification, reference being had to the accompanying drawing, forming a part thereof.

The figure is a plan view of the rear face of a playing card showing my new design. The face of the card is conventional.

I claim:

The ornamental design for a playing card, as shown and described.

GEORGE J. O'DONNELL.
